UNITED STATES PATENT OFFICE.

ROBERT N. STEVENS, OF NEW YORK, N. Y.

APPARATUS FOR APPLYING HEAT TO PAVEMENTS FOR DISINFECTING OR MELTING SNOW.

SPECIFICATION forming part of Letters Patent No. 625,711, dated May 23, 1899.

Application filed February 24, 1899. Serial No. 706,688. (No model.)

To all whom it may concern:

Be it known that I, ROBERT N. STEVENS, a citizen of the United States, residing at New York, county of New York, State of New York, have invented certain new and useful Improvements in Apparatus for Applying Heat to Pavements for Disinfecting or Melting Snow, fully described and represented in the following specification and the accompanying drawings, forming a part of the same.

The present invention relates to that class of pavement-heating machines which can be used for melting snow or destroying pathogenic animal germs; and the object of the present invention is to furnish improved means for varying the internal capacity of the flame-box, for directing the flame within the flame-box toward or from the pavement, for preventing the escape of the flame at the edges of the box, and for preventing the radiation of heat from the top and sides of the box.

The drawings illustrate a machine embodying these improvements.

Figure 1 is a side elevation of the apparatus; Fig. 2, a view of the rear end of the box; Fig. 3, a longitudinal section of the box upon line 3-3 in Fig. 2; Fig. 4, the curtains for the rear end of the box; Fig. 5, a cross-section of the box on line 5-5 in Fig. 1; Fig. 6, a front elevation of the machine; Fig. 7, a plan of the machine; Fig. 8, a perspective view of one of the side curtains, and Fig. 9 a perspective view of the body or skeleton of the flame-box without its attachments.

The body is formed of vertical sides and ends A A', stiffened at the top by a flange or angle-iron *a* and braced across the top at the rear end by two cross-bars *a'*. The box is carried by an axle *B*, supported by wheels *C* in the rear of the box and connected to the cross-bars *a'* by side rails *b*, having a handle *c* for moving the apparatus.

The roof of the flame-box is formed of a top plate *A²*, secured movably within the sides or body, so as to vary the internal height of the box at pleasure. The top plate is held adjustably within the body by chains *l*, hooked upon pins *m*, which are projected upwardly at intervals from the flange *a* upon the body, but the top plate may be adjusted and secured by any other suitable means.

The body A A' is held by the side rails and handle *c* a few inches above the pavement, and the sides and ends are provided with asbestos curtains *D*, which sweep upon the pavement and conform to its inequalities, so as to retain the flame in the box. The sides and ends are provided with rows of hooks *e* to sustain the curtains, and one of the side curtains is shown in Fig. 6 provided with two sets of eyelets *d'*, either of which is adapted to engage the hooks *e*. The curtains may thus be fixed at different heights upon the body to conform to the inequalities of the ground or to compensate for wear upon their lower edges.

A platform *b'* upon the rails *b* carries an oil-tank *E*, and a series of burners *d* is shown mounted at the rear end of the flame-box to project the flame forwardly into the same. The rear end A' is formed with notches *f* to admit the flame, and the rear curtain (shown in Fig. 4) is formed with slots *f'* for the same purpose.

The so-called "Wells" burner is represented in Figs. 1 and 2, which burner has a rectangle of tubes, through which the flame is projected to vaporize the oil before combustion.

The burners are represented in Fig. 1 suspended or projected from the lower side of a pipe *G*, which is arranged to rock in bearings *g* upon the rear end A' of the flame-box and is connected by hose *g'* and cock *G'* with the tank *E*. By mounting the burners upon the swiveling tube *G*, which supplies them with oil, they may be inclined toward the pavement, as shown in Fig. 1, or toward the top plate *A²*, as shown in Fig. 3.

A series of apertures *H* is formed in the front end of the body, and a damper-plate *H'* is applied thereto for closing or opening the apertures, and a similar damper and series of apertures may be formed upon the top plate near the front end of the flame-box, if desired.

It will be understood from the above description that the four sides of the flame-box form a skeleton body, which is fixed to the supporting carriage or axle, so as to be sustained above the pavement, while the fire-proof curtains applied to the sides of the box serve to make a contact with the uneven sur-

face of the pavement and to confine the flame in the box far more effectually than can be done with sides of rigid material.

A set-screw *k* is shown in one of the bearings *g* to clamp the burner-supporting tube *G* when adjusted with the burners in the proper position, and the burners may thus be directed downwardly when the apparatus is used in melting ice, which requires the most direct application of the heat.

The adjustability of the top plate *A*² permits the internal capacity of the flame-box to be increased when the apparatus is used for melting snow, in which case the box is directed upwardly by the depression of the handle *c* and then pressed downwardly upon the snow to be melted.

Where the apparatus is used for destroying pathogenic germs upon street-pavements, it is obvious that much less heat is required than in melting large quantities of snow or ice and that the heat must be carefully graduated when operating upon a pavement of wood or asphaltum to prevent overheating the same.

In such case the adjustability of the top plate *A*² permits the lowering of the same close enough to the pavement to radiate heat effectively upon the latter, and the flame *F* is then directed upwardly, as shown in Fig. 3, to heat the plate *A'* for such purpose and to avoid the impingement of the flame directly upon the pavement. To utilize the heat most effectively in thus sterilizing a pavement, I prefer to prevent radiation from the top and sides of the flame-box by arranging an asbestos blanket *I* over the entire flame-box, as shown in Fig. 5 and as indicated by dotted lines *I* in Fig. 9. Such asbestos blanket retains the heat in the top plate *A*² and sides *A*, and thus secures the radiation of the heat to the pavement with the least possible loss.

It is obvious that the asbestos blanket performs the same function as the asbestos curtains when placed over the flame-box and extended down the sides of the same into contact with the uneven surface of the pavement, and it may therefore be used in place of the curtains to confine the flame within the flame-box when the bottom of the flame-box does not conform with the pavement.

The essential features of the invention are the movability of the top plate *A*² within the skeleton body, the use of fireproof curtains to contact with the pavement below the edges of the body, the pivoting of the burners to direct the flame upwardly and downwardly from the plane of the flame-box, and the asbestos blanket applied over the whole flame-box to prevent radiation and to retain the flame in the box when required by extending the blanket to the pavement. It is obvious that a part of these improvements may be used without the others.

Having thus set forth the nature of the invention, what is claimed herein is—

1. In an apparatus for applying flame to a pavement, the combination, with a flame-box

body and means for traversing it over the pavement, of curtains of flexible material applied to its sides to contact with the uneven surface of the pavement and thereby confine the flame, substantially as herein set forth.

2. In an apparatus for applying flame to a pavement, the combination, with a supporting-axle having wheels upon its ends, of a flame-box body sustained by the axle above the pavement, and fireproof curtains applied to the sides of the box to contact with the uneven surface of the pavement and thereby confine the flame, substantially as herein set forth.

3. An apparatus for applying flame to a pavement, comprising a supporting-axle with wheels at the ends, a flame-box body attached to the axle, and a top secured movably within the body, substantially as herein set forth.

4. An apparatus for applying flame to a pavement, comprising a supporting-axle with wheels at the ends, a flame-box body attached to the axle and sustained thereby above the pavement, a top secured movably within the body, and fireproof curtains projected below the bottom of the body to contact with the uneven surface of the pavement and thereby confine the flame, substantially as herein set forth.

5. An apparatus for applying flame to a pavement, comprising a supporting-axle with wheels at the ends, a flame-box body formed of vertical sides with stiffening flange at the top, a top plate secured adjustably within the body, and fireproof curtains projected below the bottom of the body, as and for the purpose set forth.

6. In an apparatus for applying flame to a pavement, the combination, with a flame-box body sustained above the pavement, and provided with supporting-pins, of asbestos curtains having two or more sets of holes adapted to fit the pins so as to project the curtain a greater or less degree below the body, substantially as herein set forth.

7. In an apparatus for applying flame to a pavement, the combination, with a flame-box and a liquid-fuel reservoir, of means of sustaining the box above the pavement, and a series of liquid-fuel burners hinged at the rear end of the box to be inclined above or below the plane of the box, and suitable connections between the burners and reservoir, as and for the purpose set forth.

8. In an apparatus for applying flame to a pavement, the combination, with a flame-box and a liquid-fuel reservoir, of means for sustaining the box above the pavement, a pipe swiveled horizontally upon the rear end of the flame-box and connected with the liquid-fuel reservoir, and a series of liquid-fuel burners attached to such pipe, whereby the flame may be directed above or below the plane of the box, as and for the purpose set forth.

9. The combination, with an apparatus

having a flame-box with burners for applying heat to a pavement, of an asbestos blanket applied to the top and sides of the flame-box to prevent radiation, substantially as herein set forth.

10. The combination, with an apparatus having a flame-box with burners for applying heat to a pavement, of an asbestos blanket applied removably to the top and sides of the flame-box and also to the adjacent pavement,

to confine the flame and also to prevent radiation, as and for the purpose set forth.

In testimony whereof I have hereunto set my hand in the presence of two subscribing witnesses.

ROBERT N. STEVENS.
